UNITED STATES PATENT OFFICE.

ALFRED L. BERNARDIN, OF EVANSVILLE, INDIANA.

BOTTLE-CAP.

1,244,412.

Specification of Letters Patent. Patented Oct. 23, 1917.

Application filed March 6, 1917. Serial No. 152,691.

To all whom it may concern:

Be it known that I, ALFRED L. BERNARDIN, a citizen of the United States, and a resident of Evansville, in the county of Vanderburgh and State of Indiana, have invented 5 a certain new and useful Improvement in Bottle-Caps, of which the following is a specification.

My present invention relates generally to 10 bottle caps, and more particularly to catsup screw caps of the pieced type, prior to the production of which catsup screw caps of the length required were of the seamless or drawn type, the manufacture of which represents such a strain on the metal as to make 15 it impossible to apply lacquer or other coatings in the sheet, since such coatings would be destroyed by the drawing operation.

Since pieced cap constructions represent 20 only bending, various inexpensive coatings can be effectively applied in the sheet without appreciable damage during the making of the cap.

Pieced cap constructions up to the present 25 time have, however, presented side seams extending the full length of the cap, so that the lower or inner threaded section thereof must have a beaded inner or bottom edge in order to keep the bodies in round or truly 30 cylindrical shape. This beaded edge is not only a dirt catcher, but detracts from the appearance of the cap in general, and the pieced cap construction as now utilized is objectionable for these reasons.

35 In my present invention I aim to produce a pieced cap, the inner or lower section of which, having the threads, may be drawn by virtue of being relatively shallow and, being seamless as finished, the usual beaded 40 edge may be dispensed with.

In the accompanying drawing wherein my invention is illustrated:

Figure 1 is a perspective view of the neck portion of a bottle provided with my improved cap;

Fig. 2 is a vertical section through the cap as shown in Fig. 1;

Fig. 3 is a horizontal section taken on the line 3—3 of Fig. 2;

Fig. 4 is a side view partly broken away and in section, illustrating a slightly modified form, and

Figs. 5, 6, and 7 are partial vertical sections illustrating modified forms of joints 55 between the two pieces or sections of the cap.

As seen in the several figures, the lower or inner section 10 of the cap proposed by my invention, is of seamless construction, and threaded for engagement with the 60 threads of a bottle neck 11, this section or piece of the cap terminating in an inner or lower raw edge 12 by virtue of its seamless construction, which obviates necessity of having a surrounding bead required at the 65 lower inner edge of the pieced cap constructions now in use, by reason of their vertical seams.

The lower inner section 10 may be joined at its opposite edge to the lower inner edge 70 of the upper outer piece or section 13 of the cap, by means of an externally interlocking seam 14, as seen in Figs. 1, 2, and 3, or by any one of a number of other type seams, for instance, an internally interlocking seam 75 15, as in Fig. 5, an outer lapped folding seam 16, as seen in Fig. 6, or a crimped seam 17, as shown in Fig. 7.

It is to be understood that, in forming 80 the inner piece or section 10 of the cap, a shell is drawn up and its top blanked out, damage to the lacquer or other coating to be applied in the sheet being prevented by virtue of the comparative shallowness of 85 such shell with respect to the full length of the cap.

In Figs. 1 and 2 I have shown the upper or outer section 13 of the cap formed of a bent strip and have utilized the blanked out top of the lower seamless shell 10 as a top 90 18 for the upper section as shown. The upper section may, however, be drawn up in a single piece, as seen at 19 in Fig. 4.

It is obvious from the foregoing that the construction provided by my invention obviates the disadvantages first above referred to in two-piece cap constructions, and still renders it optional as to the particular horizontal seam between the two pieces of the cap as well as the particular construction of 100 the upper outer piece or section thereof.

Although my invention aims to do away with the too rounded lower edge of the lower section 10, as above described, it is obvious that if desired for purposes of ornamentation or to retain desired uniformity where beads have been universally used, a bead may be provided at the point indicated, even though not necessary otherwise.

In explanation of the construction of the 110 lower seamless section 10, it is to be understood that this section, of a comparatively

small depth in respect to that of the usual complete cap, enables its formation in a single drawing operation which the lacquer or usual coating will stand without material harm.

Furthermore, in connection with a seamless lower section as at 10, deeper threads may be rolled than in the seamed section so as to thereby cover greater variation in 10 the dimensions of the bottles or other articles to which the cap is applied.

It is further obvious that by the provision of a seamless lower section I obviate the provision of means to grip the upper section, unnecessary in the pieced cap, the lower section of which has a vertical seam for the purpose of pulling such seam through the thread dies, and which gripping means in the ordinary formation frequently 20 impair and go so far as to totally destroy the lacquer or coated finish of the upper part.

I claim:

1. A bottle cap having a pair of separately formed and longitudinally alined 25 shells, and a horizontal seam permanently connecting the adjacent edges of said shells, one shell of which is drawn from a single piece having its top removed, and the outer shell of which has a vertical seam and a top 30 joined by a seam thereto.

2. A bottle cap having a pair of separately formed and longitudinally alined cylindrical shells, and a horizontal seam connecting the adjacent edges of said shells, the one shell of which is drawn from a single 35 piece with its top removed, and has a raw free edge.

3. A bottle cap having a pair of separately formed and longitudinally alined cylindrical shells, and a horizontal seam 40 connecting the adjacent edges of said shells, one only of which shells is drawn from a single piece of material and threaded.

4. A bottle cap having a pair of separately formed and longitudinally alined 45 cylindrical shells, and a horizontal seam permanently uniting the abutting edges of said shells, one shell of which has a raw free edge, and is drawn from a single piece of material, and threaded for the purpose de- 50 scribed.

5. A bottle cap having a pair of shallow cylindrical shells in end to end relation, and a horizontal seam connecting the adjacent edges of said shells, the outer shell being 55 closed at its free end, and the inner shell being otherwise seamless and having threads, and a raw free edge.

ALFRED L. BERNARDIN.
